UNITED STATES PATENT OFFICE

GEORGE A. KING, OF WATERBURY, CONNECTICUT, ASSIGNOR TO SCOVILL MANUFACTURING COMPANY, OF WATERBURY, CONNECTICUT, A CORPORATION OF CONNECTICUT

MEANS FOR ATTACHING SEAT COVERS AND THE LIKE

Application filed November 1, 1927. Serial No. 230,287.

The object of this invention is to provide means for yieldingly yet securely attaching loose articles to a fixed article, in such way that strains placed upon the loose article will more or less fully be taken up by the attaching medium to thereby prevent injury of the fixed article.

In order to illustrate a special application of my invention, but without thereby limiting the scope of the invention or its utility, I will explain it in connection with seat covers for automobiles. Heretofore these seat covers have been applied to the upholstery of the seats by means of pins stuck 15 in the upholstery and engaging the covers, but when in use, the movement of the occupants of the seats produces more or less severe and sometimes sudden strains sufficient to move the pins and tear the upholstery.

The present invention is designed to remove, or at least alleviate, this injurious action, and to this end the covers are supplied with an elastic medium, and the pins are 25 provided with pivoted hooks which engage the elastic medium, thus forming an indirect connection of the covers with the seats, instead of directly connecting the covers with the seats as commonly done heretofore, as I will proceed now to explain more fully and finally claim.

In the accompanying drawings illustrating the invention, in the several figures of which like parts are similarly designated, 35 Figure 1 is a plan view, partly in section and partly broken away, illustrating one embodiment of the invention. Fig. 2 is a cross section taken on line 2-2 of Fig. 1. Fig. 3 is a perspective view of one form of 40 hook-pin.

The cover 1, at or near its upper edge, is supplied with a number of openings, such as eyelets 2, suitably spaced, and reeved through these openings is a flexible, elastic 45 cord or spring 3, suitably anchored at both ends of the cover, as by knots 4. Any desired degree of slackness may be placed in the elastic medium. This slackness may be utilized to form loops which may be engaged with any suitable holding medium

placed on a fixed body, such as the upholstered back 5 of an automobile or other seat, so that when the seat is in use the movements of the occupant, effective on the loose cover, will be taken up by the elastic 55 medium, and the incident strain will be greatly modified, if not entirely overcome, with relation to damaging effect on the seat or its upholstery.

The upper edge of the cover may be provided or made with a bib 6, that may be turned up over and used to conceal the elastic medium and its engaging devices.

The particular form of engaging device herein shown, comprises a double pronged 65 or pointed pin 7, having pivoted or hinged to its head 8 a swinging hook 9, with which the loops of the elastic medium are engaged. The pins are stuck in the upholstery of the seat at intervals to engage 70 the loops of the elastic medium. The hook member of the pin may be provided with a rearwardly and upwardly extending pointed projection 10, which is adapted to enter the upholstery to prevent the accidental escape of the pin.

While I prefer to use the hinged hook-pin, and especially one with a retaining prong, yet it is within my invention to use other means for engaging the elastic medium of the cover to secure the cover in place on the seat.

Variations in the details of construction and arrangement are permissible within the principle of the invention and the scope 85 of the claims following.

What I claim is:

1. The combination of a seat cover having openings arranged at intervals at or near one edge thereof and an elastic medium 90 loosely reeved through said openings and attached at both of its ends to said cover so as to afford a series of loops, and pivoted hooks having downwardly projecting prongs adapted to be attached to a fixed 95 part of the seat in position to engage the several loops of the elastic medium and to support the cover yieldingly in position.

2. The combination of a seat cover having an elastic cord associated therewith, the 100

said cover being provided with means for loosely holding said cord at intervals leaving portions of said cord exposed to form a series of loops, and pivoted hooks having downwardly projecting prongs adapted to be attached to a fixed part of the seat in position to engage the several loops of the elastic medium and to support the cover yieldingly in position.

10 In testimony whereof I have hereunto set my hand this 29th day of October, A. D. 1927.

GEORGE A. KING.
